SWITCH

Filed Sept. 20, 1929

FIG. 1

FIG. 2

FIG. 3

INVENTOR
LLOYD THOMAS ROBERTON
BY

Harry Lee Dodson
ATTORNEY

UNITED STATES PATENT OFFICE

LLOYD THOMAS ROBERTON, OF MILWAUKEE, WISCONSIN

SWITCH

Application filed September 20, 1929. Serial No. 393,879.

My invention relates to switches which are used where it is desirable to have a plurality of electrical circuits which can be selectively controlled by a single handle, and in which two circuits may be closed by the one handle.

My invention relates more specifically to a switch for use in radio circuits where there is remote control of the set,—such a system, for example, as is described in my copending application for Letters Patent, Serial No. 402,389, in which I describe the need of a switch of this type.

My invention has for its object, to simplify the construction of the switch and connect four circuits, any one of which may be closed by moving the switch handle, and in which two circuits may be closed by practically the same movement of the switch.

My means of accomplishing the foregoing objects may be more readily understood by reference to the accompanying drawings, which are hereto annexed and are a part of this specification, in which—

Fig. 1 is a top or plan view of a switch constructed in accordance with my improvement;

Fig. 2 is a side elevation of the same; and Fig. 3 is an end elevation.

Similar reference numerals refer to similar parts throughout the entire description.

As shown in the drawings, my switch comprises a base plate 1 formed of suitable insulating material. This base 1 has posts 2, 3, 4 and 5, which are rigidly mounted thereon. These posts are provided with clips 6, 7, 8 and 9, of standard construction, to which may be attached the wires of the various circuits.

The switch handle is mounted on the base plate 1 midway between posts 2 and 3, and consists of a post 10, which is tiltable and rotatable, as clearly seen in the drawings, being loosely mounted in an opening 11 in the base plate 1. A coil spring 12 is mounted on the post 10, and bears against a washer 13 which rests on the base plate 1, and a similar washer 14 which engages a shoulder 15 formed on the post 10. The result of this construction is that the spring 12 holds the post 10 normally in a vertical position, while it may be tilted from side to side when de-

sired. A knob 16 is secured to the top of the post 10 for its convenient manipulation. Contact points 17 and 18, of suitable material, are mounted in the sides of the post 10, in position to register and contact with contact points 19 and 20 mounted in screws 21 and 22, which are adjustably mounted in posts 2 and 3, lock nuts being provided to secure the screws 21 and 22 in adjusted position. An arm 23 is mounted in the post 10, and extends outwardly therefrom. This arm 23 has contact points 24 and 25 mounted thereon, which are in register with contact points 26 and 27, which are mounted in screws 28 and 29 mounted in posts 4 and 5. These points are adapted to make contact when the arm 23 is swung to the right or left respectively. The screws 28 and 29 are adjustable in posts 4 and 5, lock nuts 30 and 31 being provided to secure the adjustment when made. The post 10 is connected by an electric conductor to a suitable source of electric current, as a battery (not shown), this wire being the third or common wire, so called.

Mounted upon the posts 2 and 3 is a piece of insulated material 32, which is provided with a slot 33 which permits the post 10 to tilt. The ends of the insulation 32 have lateral extensions 34 and 35, to which are secured the ends of coil springs 36. The other ends of these springs 36 are secured to the ends 37 and 38 of a rod which is mounted in the post 10. These springs 36 serve to hold the arm 23 normally out of contact with the points 26 and 27.

The operation of the switch is as follows: Assuming it is desired to close the circuit through post 3, the operator grasps the knob 16 and tilts the post 10 until the contact point 18 contacts point 20 in the screw 22 in post 3, thus closing this circuit. Now, if it is desirable to close the circuit through either post 4 or 5, all that is necessary for the operator to do is to rotate the knob 16 (while still holding the circuit closed through points 18 and 20) until the contact point on the arm 23 contacts either the contact point 26 or 27 as is desired, and the circuit through either post 4 or 5 will be closed, as the case may be.

It will be apparent from the foregoing, that

upon releasing the knob 16 the coil springs 36 will automatically return and hold the post 10 in the open position, and all the circuits will be open. It is also plain that the 5 knob 16 can be rotated to close the circuit through either post 4 or 5 without closing either circuit through posts 2 and 3, or that after the circuit through either post 4 or 5 is completed then the post 10 may be tilted either way and a circuit completed through either post 2 or 3.

Although I have shown a specific embodiment of my invention, it is only to illustrate a preferred form thereof, and I do not wish 15 to be understood as limiting myself to the form illustrated and described, except as such limitation appears in the claims.

Having described my invention, what I regard as new, and desire to secure by Letters 20 Patent of the United States, is:

1. In a multiple contact switch, a plurality of contacts, a post secured to a source of current supply, contacts on said post, means to hold said contacts normally out of contact 25 with the first named contacts, and means to close one or more of said contacts.

2. In a multiple contact switch, a plurality of contacts, a tiltable post connected to a source of current supply, contacts on said 30 post, means to hold said contacts normally out of contact with said first named contacts, and means to close one or more of said contacts.

3. In a multiple contact switch, a plurality of contacts, a rotatable and tiltable post connected to a source of current supply, contacts on said post, means to hold said contacts normally out of contact with the first named contacts, and means to close one or more of 40 said contacts.

4. In a multiple contact switch, a base plate, a plurality of contacts, a post connected to a source of current supply, contacts on said post, means to hold said contacts normally out of contact with the first named contacts, and means to close one or more of 45 said contacts.

5. In a multiple contact switch, a base plate, a plurality of posts on said base plate, a plurality of contacts in said posts, a rotatable and tiltable post connected to a source of current supply, contacts on said post and an arm on said post, contacts on said arm, means to hold said contacts normally out of contact 55 with the first named contacts, and means to close one or more of said contacts.

6. In a multiple contact switch, a base plate, a plurality of posts mounted thereon, adjustable contacts mounted in said posts, 60 means to connect electrical conductors to said posts, a rotatable and tiltable post, contacts on said post adapted to engage certain of the said first named contacts when the post is tilted, an arm on said post, contacts on said 65 arm adapted to engage certain of said contacts when the post is rotated, and a spring which holds said contacts on said rotatable and tiltable post normally out of engagement with the first named contacts.

7. In a multiple contact switch, a base plate 70 of insulating material, a plurality of posts fixedly mounted thereon, a plurality of screws adjustably mounted in said posts, contacts on said screws, means to connect said posts to electrical conductors, a slot in said base plate intermediate two of said posts, a post mounted in said slot, a coil spring, surrounding a portion of said post, which holds said post normally in a vertical position, a knob on said post, said post being connected to a source of electrical supply, an arm which extends intermediate two of said first named posts, contacts on said arm which engage the contacts on the screws when the post is rotated, and springs which hold the contacts on the arm normally out of contact with the contacts on the screws.

8. In a multiple contact switch, a base plate, a plurality of posts mounted thereon, adjustable contacts mounted in said posts, means to connect electrical conductors to said posts, a rotatable and tiltable post, contacts on said post adapted to engage certain of said first named contacts when the post is tilted, an arm on said post, contacts on said arm adapted to engage certain of said contacts when the post is rotated, a spring which holds said contacts on said rotatable and tiltable post normally out of engagement with the first named contacts, and means to hold the contacts on said arm out of contact with the contacts on said posts.
